COMBINATION TOOTHBRUSH, CLOSURE CAP
AND DENTIFRICE CONTAINER

Arthur A. Gleichert, Birmingham, Ala., assignor of one-half to Robert J. Bales, Fairhope, Ala.

Filed Dec. 19, 1966, Ser. No. 5,093

Term of patent 14 years

(Cl. D4—18)

Fig. 1

Fig. 2

Fig. 3

Fig. 4

Fig. 5

Fig. 6

FIG. 1 is a top plan view of a combination toothbrush, closure cap and dentifrice container showing my new design;

FIG. 2 is a side elevational view thereof;

FIG. 3 is a sectional view taken along the line 3—3 of FIG. 2;

FIG. 4 is a bottom plan view thereof;

FIG. 5 is an end elevational view thereof taken from the left of FIG. 2;

FIG. 6 is an elevational view thereof taken from the right of FIG. 2; and

FIG. 7 is a perspective view thereof, showing the closure cap removed therefrom.

I claim:

The ornamental design for a combination toothbrush,

closure cap and dentifrice container, as shown and described.
